PORTABLE DRINKING FOUNTAIN

Henry E. Brandt, St. Paul, Minn.

Application February 18, 1938, Serial No. 191,231

2 Claims. (Cl. 299—16)

This invention relates to a drinking device or fountain and particularly to such a device which is easily portable and which may be conveniently carried about by one person in the use thereof.

It has long been the custom to supply various crews of workmen with drinking water which has carried to them by an attendant. One common way of carrying such water to construction and other crews was to have the water in a bucket and serve the same with a cup or dipper. With this practice trouble has been experienced on account of the transmission of disease from one member of the crew to another. In some cases an epidemic of trench mouth or Vick's disease has been caused by such practice and it is probable that other infections have been so transmitted.

It is desirable therefore, to have some sanitary method of not only carrying the water to the workmen but some way for them to drink the water without danger of contamination.

It is an object of this invention therefore, to provide a simple and efficient portable drinking device by means of which water can be carried in a clean and sanitary condition and by means of which the workmen or other persons may conveniently be served.

It is a further object of the invention to provide a portable drinking device comprising a liquid container, preferably of the upstanding type, said container having a bubbler device secured thereto with means for delivering the water to said bubbler device and means for controlling the flow of liquid therethrough.

It is still further an object of the invention to provide a portable drinking device comprising a container having a comparatively large filling opening in the top thereof so that it can be easily filled and cleaned, a removable cover for the opening, means for tightening or loosening said cover comprising a handle disposed above and preferably centrally of said container, said handle functioning to tighten and loosen said cover and also to operate a air pump disposed within the container and provided with means for discharging air into said container adjacent said cover.

These and other objects and advantages of the invention will be fully set forth in the following description made in connection with the accompanying drawings in which like reference characters refer to similar parts throughout the several views and in which:

Fig. 1 is a view in side elevation of the device;
Fig. 2 is a top plan view thereof;

Fig. 3 is a view partly in side elevation but mostly in central vertical section; and

Fig. 4 is a vertical section taken substantially on line 4—4 of Fig. 2 as indicated by the arrow.

Referring to the drawings a portable drinking device is shown comprising a container 10. While said container may be made of various forms, in the embodiment of the invention illustrated it is shown as of elongated cylindrical form adapted to stand upright. Said container has a substantially horizontal bottom 10a and has an inwardly curved top portion 10b terminating in a circular bead 10c which defines a comparatively large opening in the top of the container through which it may be filled. A cylindrical casing 11 surrounds container 10, the cylindrical wall of which and the horizontal bottom portion of which are spaced from the corresponding portions of container 10. Casing 11 also has an inwardly curved top portion 11a, the inner edge of which engages the top 10b of container 10. The space between container 10 and casing 11 will be filled with some good insulating material or compound. A cover 12 is provided having a central upwardly directed dome-like portion 12a, an intermediate portion slightly concave on its upper side and an outer annular trough-shaped portion 12b. The portion 12b has its open side directed downwardly and receives and holds an annular gasket 13 which will be made of some suitable yielding material such as rubber or rubber composition. Gasket 13 rests upon the top of the bead 10c and forms a tight seal therewith to thus tightly close the container 10. The central portion 12a is centrally apertured to receive a lower reduced threaded portion 14a of a plug 14. A nut 15 is threaded on the portion 14a so that portion 12a is disposed between nut 15 and a shoulder on the plug 14. Plug 14 is exteriorly threaded through its main or central portion and screws into the central threaded portion of a bar 16 which extends transversely across the top of and some distance beyond cover 12. Bar 16 has short vertical projections 16a extending upwardly at its ends and said bar is adapted to be received in slots 17a extending laterally into ears or lugs 17 formed of comparatively thin plates extending vertically at either side of container 10. While lugs 17 might be variously formed and secured, in the embodiment of the invention illustrated they are shown as having their lower ends extending through the top of container 10 and along the inner side of the top portion 10b to which they are secured in any suitable manner as by welding. As shown in Fig. 1 the slots 17a extend upwardly a short distance above the outer horizontal edge of lugs 17, or in other words said slots are slightly

reentrant. Plug has an outwardly extending flange 14b at its top which is provided on its underside and at opposite sides with a pair of rectangular slots 14c. Another pair of slots 14e extend vertically through flange 14b midway between slots 14d. Said plug is also provided at its upper end with a vertical bore 14d. A coiled compression spring 18 is disposed in bore 14d and surrounds a plunger rod 19 which at its upper end is rigidly secured to a handle member 20. Handle 20 has a substantially semi-circular or U-shaped portion the arms of which are directed upwardly and have revolvably mounted in their upper ends and extending therebetween a grip portion 20a of substantially cylindrical form, the same being slightly tapered toward either end. Handle 20 has a flange 20b at its lower side from the opposite sides of which depend lugs 20c having inwardly extending portions 20d adapted to be received in the slots 14c. The lower open end of portion 12a is slightly less in diameter than its upper curved or dome-like portion and the upper end of a pump cylinder 21 has an outwardly extending bead 21a at its upper end received in portion 12a. Portion 12a at opposite sides has inwardly pressed parts or indentations 12c and the bead 21a is adapted to be pressed past these parts and thus to be removably held in portion 12a. Cylinder 21 is thus revolvably connected to portion 12a and it may also be stated that plug 14 is connected to portion 12a for rotative movement relative thereto. Plunger rod 19 has a threaded portion adjacent its lower end on which is adjustably secured a nut 22. A spring 23 of the coiled compression type surrounds rod 19 above nut 22 and acts as a buffer to engage the lower end of plug 14 when rod 19 is lifted. A plunger 24 is secured to the lower end of rod 19 being held between an upper plate 25 and a lower plate 26, the latter being engaged by a nut 27 threaded onto the lower end of rod 19. A compression coiled spring 28 is disposed between plate 25 and nut 22. Plunger 24 is provided with some apertures 24a. Should the pressure created by the pump be sufficient to compress spring 28, plate 25 would be lifted and the pressure relieved. Nut 22 can be adjusted to adjust the tension of spring 28 so that the amount of pressure to be created by the air pump compressing cylinder 21 and plunger 24 can be regulated. The lower end of cylinder 21 has a recess 21b extending laterally therefrom communicating through a small hole 21c with a valve chamber 21d. A ball check valve 29 is disposed in the chamber 21d adapted to rest on a seat, closing opening 21c or to be raised against a seat formed on the lower end of a tube 30 and close the opening therethrough. Tube 30 extends from the top of chamber 21d to a point adjacent the cover 12 and thus to a point adjacent the top of the container 10. Tube 30 is shown as held adjacent its upper end in a small angle bracket 31 secured to the upper end of cylinder 21.

Container 10 has secured at one side to the portion 10b a boss or portion 10d. Said portion 10d is provided with a threaded bore at its lower end in which is secured the upper end of a tube 32 which extends downwardly to a point adjacent the bottom of container 10 where it is preferably surrounded by a screen member 33. Portion 10d is also provided with a threaded bore at its upper and outer end in which is secured the lower reduced and threaded portion 34a of a valve casing 34 which extends upwardly and outwardly from the portion 10b of container 10 and has a central

bore therein. Portion 10d is provided with an aperture 10e which communicates with the lower end of a passage 34b extending centrally of the valve casing 34 and into the bore thereof. A valve seat is formed at the upper end of passage 34b with which engages a valve 35 preferably formed of some yielding material such as rubber. Valve 35 is held on the lower reduced portion of a short stud 36 secured in the lower end of a tube 37. A washer 38 is disposed at the lower end of tube 37 against which rests a small disk or washer 39. A compression coiled spring 40 surrounds tube 37 seating at its lower end against disk 39 and at its upper end against another disk or washer 41 engaging a packing member or washer member 42 which surrounds tube 37 and seats against a plug 43 threaded into the top of valve casing 34. Tube 37 is provided with a plurality of holes 37a therein above stud 36. Plug 43 has a hexagonal flange at its upper end between which and the top of the valve casing 34 is clamped the lower horizontal portion of a guard member 44. Guard member 44 is of considerable width and concave on its outer side and extends some distance above valve casing 34. Tube 37 extends upwardly through a central bore in plug 33 and has its upper end exteriorly threaded to receive a bubbler head or member 45 having a semi-spherical upper end and a central discharge outlet 45a. The lower portion of bubbler 45 is of hexagonal shape and is disposed some distance above the top of plug 43. A valve lever or handle 46 formed of a small bar shown as having parallel sides is apertured at its outer end to surround tube 37 between members 43 and 45. In other words, tube 37 passes through the aperture in handle 46. Handle 46 extends inwardly through a slot 44a in guard 44 and is then curved upwardly and inwardly in a compound curve. A handle 47 is formed of a rod extending in slightly convex form above and around the top portion 10b of container 10 and at the side opposite valve casing 34 said handle having its ends reversely bent and secured to the outer side of portion 10b in any suitable manner as by welding. Casing 11 has secured to its side beneath and centrally aligned with handle 47 a clip bracket 48 in which is oscillatably mounted a triangular link 49. Link 49 is adapted to receive a strap or snap hook which may be provided for carrying the device.

In operation the water or liquid to be supplied for drinking purposes will be placed in container 10, cover 12 being removed for this purpose. To remove cover 12 handle 20 will be grasped and pushed downward against the tension of spring 18, lug portions 20d passing through slots 14e and then being aligned with and disposed in slots 14c by upward movement of said handle 20. Handle 20 can now be rotated in a counter clockwise direction to rotate plug 14. This will relieve any pressure on cover 12 and bar 16 will be released from any pressure against lugs 17 and can now be depressed slightly and rotated in a counter clockwise direction to pass out of slot 17a and out of contact with lugs 17. The cover 12, bar 16, plug 14, handle 20 and attached parts can now be lifted from the container. The wide opening at the top of the container is now unobstructed and liquid can be easily poured therethrough into the container. To close the container the cover will be placed in position with the cylinder 19 extending downwardly into the container, bar 16 will be swung in a clockwise direction to move into the slot 17a and again en-

gage lugs 17. Lugs 20c will again be engaged with flange 14b as described and plug 14 will be turned in a clockwise direction. This will press downwardly on cover 12 and gasket 13 and cause a reacting pressure on bar 16 upward against lugs 17. Cover 12 is thus firmly clamped in place with gasket 13 pressing against the top of bead 10c. Lugs 20c are then disengaged from flange 14b and handle 20 can be reciprocated to operate plunger 24 in pump cylinder 21. Air is thus pumped through said cylinder 21 and through tube 30, the same passing out at the top of said tube adjacent the top of the container so that it will not pass through the liquid in the container. It may be stated that the air passes into the cylinder around rod 19 which fits loosely in plug 14. Air pressure is thus built up in container 10 on top of the liquid and as above stated, this air pressure will be limited by the tension of spring 23. The device is now ready for dispensing and the person desiring a drink of the liquid will place his mouth above bubbler 45 and adjacent guard 44 and press downwardly with his fingers on the inner end of lever or handle 46. Handle 46 fulcrums on guard 44 and the outer end thereof will raise bubbler 45 and tube 47 and lifts valve 35 from its seat. The air pressure on the liquid forces the same through screen 33 into the lower end of tube 32 upwardly through said tube and through aperture 10e and passage 34b. When valve 35 is lifted the liquid passes into the bore of valve casing 34 through holes 37a and upwardly through tube 37 and through passage 45a in member 45. The liquid will thus be directed upwardly into the mouth of the person disposed above member 45. The guard 44 prevents the person or drinker from mouth of the person disposed above member 45. This prevents contamination and acts to prevent the transmission of any germs or diseases. When the drinker has finished he will release handle 46 and spring 40 will move tube 37 downwardly and valve 35 will be moved against its seat so that the discharge of water through passage 34b will be stopped. All that is necessary for the drinker to do is merely to press on the valve handle 46.

The device can be easily carried by the handle 20. It will be noted that spring 23 and spring 18 act as buffers the latter being engaged by the underside of handle 20. The device may also be carried by the handle 47 if desired and particularly when the cover is removed.

The pump cylinder 21 can be removed from the cover 12 by exerting sufficient pressure thereagainst.

It will also be seen that all of the parts are quite accessible. Plug 43 can be removed to give access to valve casing 34. As stated, a strap may be secured to member 49 and handle 47 and the device carried over the shoulder if this is desired. By providing the insulation between members 10 and 11 the water or other liquid may be kept at a low temperature.

From the above description it is seen that I have provided a simple and efficient and compact portable drinking device and one that is pleasing in appearance. The casing 11 will be suitably coated to have a pleasing and non-corrosive surface. Guard 44, bubbler 45, casing 34 and the

top of the casing 10 will all be nicely plated preferably with chromium plating. Handle 20 and bar 16 will be nicely finished so that a very desirable device is produced. It will be noted that 5 pump cylinder 21 does not extend a great distance into the casing 10 and no part of the liquid can get into the pump cylinder. The air pumped into the container is not passed through the liquid and objectionable foaming or frothing is 10 prevented and there is no mixing of any substances in the air with the liquid. The device is made quite rugged so as to withstand any shocks or contacts to which it may be subjected in its ordinary use. The device has been thoroughly 15 demonstrated in actual practice and is being commercially made.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

25. What is claimed is:

1. In a drinking device adapted to be connected to a container, a hollow stem extending upwardly through which water passes from said container, a valve in said stem, a pipe connected to said valve 30 forming a valve rod extending through the top of said stem and spaced from the interior wall thereof, a bubbler head secured to the upper end of said pipe above said stem, a spring for moving said valve to closed position, said pipe having a 35 perforation therein above said valve within said stem, a concavo-convex plate disposed at one side of and extending above said stem having its concave side directed toward said stem and forming a guard, a lever surrounding said pipe and engaging the lower side of said bubbler head to raise said pipe and open said valve to permit the flow of liquid through said stem and head, said lever extending through and being fulcrumed on said plate.

45. 2. In a drinking device adapted to be connected to a container and to be directed upwardly and rearwardly, the combination of a stem having a lower threaded end by which it is secured and having a cylindrical chamber therein, a valve seat at the lower end of said chamber, a valve cooperating with said seat, a pipe secured to the upper end of said valve forming a valve rod and extending through the top of said stem, said stem being closed about said pipe at its upper end, said 50 pipe being spaced from the wall of said chamber from said valve seat to said closed end, a bubbler head secured to said pipe at the upper side of said stem, said pipe having a perforation therein above said valve in said chamber, a guard of 55 concavo-convex form disposed above and at one side of said stem with its concave side toward said stem, means for moving said valve to closed position and a lever extending through and fulcrumed on said guard for raising said pipe and valve to open the latter for causing a flow of liquid through said perforation, pipe and bubbler head.

HENRY E. BRANDT.
